INVENTOR-
EDWARD J. RANTSCH
BY Edward J. Rantsch
ATTORNEY-

UNITED STATES PATENT OFFICE

EDWARD J. RANTSCH, OF HOLLIS, NEW YORK, ASSIGNOR TO HILL-INDEPENDENT MANUFACTURING COMPANY, OF GERMANTOWN, PENNSYLVANIA

ALL ALUMINUM POCKET SEAL

Application filed October 19, 1932. Serial No. 638,449.

This invention relates to new and useful improvements in seals and has more particular reference to a novel all aluminum pocket seal.

5 The invention has for an object the construction of a seal which is characterized by a body of substantially U-shape but turned upon one side and having the front of the bottom arm enlarged for receiving the base die 10 of the seal for coaction with a movable die adapted to be slidably supported in the top arm, and said body being formed with a rear extension for resting upon the surface of a desk and forming a foot in conjunction with 15 the front part of the bottom arm so that the seal may rest in an upright position upon a desk or other surface.

It is a still further object of this invention to construct the top arm of the body previously mentioned with a pair of parallel side flanges at the top and at the front adapted to encase various moving parts of the seal.

As a still further object of this invention it is proposed to arrange a handle in conjunction with the body of the seal in a manner so that the handle is substantially of L-shape and disposed with the long arm in the channel formed by the flanges previously recited and a short arm also located in the 30 channel at the front of the top arm of the seal, in a manner so that the greater portion of the handle is hid from view.

Furthermore, it is proposed to arrange a spring for moving the handle to its open position, in cavities between the handle and the body so that it is not exposed to view.

Still further as another object of this invention it is proposed to provide a link connection between the handle and a sleeve in 40 turn connected with the movable die of the seal, said link being arranged beneath the handle and within the flanges on the top arm of the body so as not to be exposed.

Another one of the objects of this invention is the arrangement of a stop for limiting the opened position of the handle which stop comprises a surface upon the small arm of the handle adapted to abut against a portion of the body upon pivoting of the handle.

50 Still further an arrangement is proposed

whereby a handle lock is mounted upon said handle and provided with a cam surface adapted to lock the handle in the closed position.

A still further object of the invention is 55 the construction of the body so that the U-shape is quite deep and adapted to eliminate the necessity of bending paper which is engaged within the seal to be impressed.

Furthermore the invention contemplates 60 the construction of a pocket seal as mentioned which is simple and durable and which may be manufactured and sold at a reasonable cost.

For further comprehension of the invention, and of the objects and advantages thereof, reference will be had to the following description and accompanying drawing, and to the appended claims in which the various 65 novel features of the invention are more particularly set forth.

In the accompanying drawing forming a material part of this disclosure:—

Fig. 1 is a side elevational view of a pocket seal constructed according to this invention. 75

Fig. 2 is a plan view of Fig. 1.

Fig. 3 is a side elevational view of the body of the seal, per se.

Fig. 4 is a front elevational view of Fig. 3.

Fig. 5 is a plan view of Fig. 3. 80

Fig. 6 is a side elevational view of the handle used in the pocket seal.

Fig. 7 is a bottom view of Fig. 6.

The pocket seal according to this invention comprises a body of substantially U-shape but turned on one side so as to have a bottom arm 10 and a top arm 11. The bottom arm 10 has its front portion formed with a circular enlargement 12 adapted to receive the stationary portion 13 of the die for the seal. 85 The rear of the body is formed with an extension 14 arranged so as to have its extremity rest upon the same surface as the bottom of the arm 10, at the point 15, forming a substantially three point support from the seal to support it in an upright position. Furthermore, the extension 14 forms a stationary handle of the seal. It is provided with an aperture 16 through which the finger may be passed when the seal is used for convenience 90 95 100

in pressing the jaws together. The top arm 11 of the body is formed with a pair of parallel flanges 17 along the sides thereof. These flanges also extend down the front end 5 of the arm 11. The bend between the arms 10 and 11 is reinforced by a flange 18 so as to form a sturdy construction.

In conjunction with the body of the seal there is a movable handle of substantially L- 10 shape having a long arm 19 and a short arm 20. The long arm 19 is adapted to rest in the top channel between the flanges 17 and extend to a position directly over the extension 14. The short arm 20 engages in between 15 the flanges 17 at the front of the arm 11 of the body. The movable handle is pivotally connected upon the body with a pintle pin 21 engaged through the flanges 17 and the handle at the junction of the long and short arms. 20 The inner face 22 of the short arm 20 of the handle is formed at an inclination adapted to act as a stop against a vertical face 23 formed upon the body of the seal. When the faces 22 and 23 engage each other the 25 movable handle will be in a raised position.

In conjunction with the stationary die section 13 there is a movable die 24 which has a top projection 25 secured by a pin 26 to a sleeve 27. The sleeve is formed with a recess 30 adapted to receive the projection 25. The sleeve 27 slidably engages in a vertical opening 28 formed in the seal body. The upper end of the sleeve 27 is formed with a transverse cut 29 in which the lower end of a link 30 is disposed. A pin 31 engages through the sleeve 27 and the link 30 for pivotally connecting these parts. The upper end of the link 30 engages into an opening 32 formed in the movable handle. A pin 33 is engaged 40 through the upper end of the link 30 and through the movable handle for pivotally connecting these parts. The movable handle is normally urged away from the extension 14 by an expansion spring 34 located between 45 the movable handle and the top of the body, and more particularly disposed respectively in circular recess 35 formed in the adjacent faces of the movable handle and the seal body. The spring 34 is located immediately adjacent 50 the link 30 so as to urge the rear end of the movable handle away from the extension 14.

A means is provided for normally locking the movable handle 19 in the lowered position shown in Fig. 1. It is advisable to so 55 hold the movable handle in that the seal is then closed and then dirt and grit cannot enter between the seal dies. Moreover the seal is more compact with the handle closed. The means for locking the movable handle 60 closed, comprises a handle lock of substantially L-shape having a long arm 36 and a short arm 37. This handle lock is disposed in a channel formed in the short arm 20 of the movable handle. A pin 38 engages 65 through the short arm 37 of the handle lock

and the movable handle for pivotally connecting these parts. The short arm 37 of the handle lock is in the form of a cam having a point 39 further spaced from the pivot 38 than another point 40. When the handle lock 70 is in a position shown in Fig. 1, the point 39 is past the dead center of pivoting of the handle lock clockwise so that it is securely held in place. The free end of the arm 36 of the handle lock may be pivoted anti-clockwise to release the movable handle. In the latter mentioned position the point 40 on the handle lock will be disposed towards the surface 23.

The pocket seal is well adapted to be made from aluminum so that it is light in weight. All parts except the pintle pins and the spring 34 could be made of aluminum. The operation of the seal consists in pivoting the handle lock so as to release the movable handle and then paper or other matter to be impressed may be engaged between the dies of the seal and the movable handle depressed to operate the seal. As the movable handle is moved downwards, motion will be transmitted by the link 30 to the sleeve 27 and finally to the movable die 24.

While I have illustrated and described my invention with some degree of particularity, I realize that in practice various alterations 75 therein may be made. I therefore reserve the right and privilege of changing the form of the details of construction or otherwise altering the arrangement of the correlated parts without departing from the spirit of the 100 scope of the appended claims.

Having thus described my invention, what I claim as new, and desire to secure by United States Letters Patent is:—

1. In a pocket seal, a body of substantially U-shape but turned around on a side and having a rear extension forming the stationary handle of the seal, a movable handle of substantially L-shape pivotally mounted upon the top of said arm of said body in a manner so that the long arm extends across the top of the top arm and the short arm extends downwards across the front of the top arm of said body, the inner face of the short arm being adapted to act against a portion of said body, for limiting pivoting of said movable handle to the open position, a stationary die section upon the bottom of said body, a movable die section above said stationary die section, a sleeve connected with said movable die section and slidably extending into an opening in said body, a link pivotally connected with the top of said sleeve and pivotally connected with said movable handle, a spring connecting between said movable handle and body for normally urging the movable handle into the open position, and a locking element adjustably mounted upon the short arm of said movable handle for en- 130

gaging against said body and holding said movable handle in the closed position.

2. In a pocket seal, a body of substantially U-shape but turned around on a side and having a rear extension forming the stationary handle of the seal, a movable handle of substantially L-shape pivotally mounted upon the top of said arm of said body in a manner so that the long arm extends across the top of the top arm and the short arm extends downwards across the front of the top arm of said body, the inner face of the short arm being adapted to act against a portion of said body for limiting pivoting of said movable handle to the open position, a stationary die section upon the bottom of said body, a movable die section above said stationary die section, means for causing the movable die section to operate and associated with the opening and closing of said movable handle, means for normally urging the movable handle into the open position, and a locking element adjustably mounted upon the short arm of said movable handle for engaging against said body and holding said movable handle in the closed position.

3. A pocket seal, comprising a body of substantially U-shape but turned around on a side and having a rear extension forming the stationary handle of the seal, a movable handle of substantially L-shape pivotally mounted upon the top arm of said body in a manner so that the long arm extends across the top of the top arm and the short arm extends downwards across the front of the top arm of said body, the inner face of the short arm being adapted to act against a portion of said body for limiting pivoting of said movable handle to the open position, a stationary die section upon the bottom arm of said body, a movable die section above said stationary die section, means for causing the movable die section to operate and associated with the opening and closing of said movable handle, means for normally urging the movable handle into the open position, and a handle lock for locking said movable handle in the depressed condition comprising a substantially L-shaped member pivotally mounted upon said movable handle and having a cam surface adapted in a certain position of said movable handle to engage a portion of said body for holding the movable handle closed and being capable of pivoting to another position in which the movable handle is free to open, in the locked position of said handle lock the point of contact between the cam surface and the body being past the dead center of pivoting of said handle lock.

5. In a pocket seal, a body of substantially U-shape but turned on one side and having a rear extension forming a stationary handle and also a foot for supporting the seal in the vertical position, a movable handle of substantially L-shape disposed with the long arm at the top of said top arm and the short arm in the front of said top arm and pivotally mounted on said body, the inner side of said short arm being engageable against a portion of said body to limit pivoting of the movable handle to an open position, a stationary die section upon the top of the bottom arm of said body, a movable die above said stationary die section, a sleeve attached upon said movable die and slidably engaged in an opening in said body, a link pivotally connecting said sleeve and said movable handle, and resilient means urging said movable handle into its open position, said resilient means comprising an expansion spring acting between said movable handle and said body and having its ends disposed respectively in cavities formed in adjacent faces of said movable handle and body.

6. A pocket seal, comprising a body of substantially U-shape but turned on one side and having a rear extension forming a stationary handle and also a foot for supporting the seal in the vertical position, the top arm of said body being formed with a pair of parallel flanges at the top and at the front side, a movable handle of substantially L-shape disposed with the long arm in the channel at the top of said top arm and the short arm in the channel in the front of said top arm and pivotally mounted to said flanges at the junction, the inner side of said short arm being engageable against a portion of said body to limit pivoting of the movable handle to an open position, a stationary die section

4. A pocket seal, comprising a body of substantially U-shape but turned around on a side and having a rear extension forming the stationary handle of the seal, a movable handle of substantially L-shape pivotally mounted upon the top arm of said body in a manner so that the long arm extends across the top of the top arm and the short arm extends downwards across the front of the top arm of said

upon the top of said body, a movable die above said stationary die section, means for causing the movable die section to operate and associated with the opening and closing of said movable handle, means for urging said movable handle into its open position, and a handle lock of substantially L-shape with the long arm disposed in a channel formed in the short arm of said movable handle, 10 a long arm of said handle lock being adapted

for manually moving of said handle lock, and the short arm of said handle lock being formed with a cam surface adapted to engage a portion of said body in one position to hold said movable handle locked, said handle lock being pivotally mounted upon said movable handle.

In testimony whereof I affix my signature.

EDWARD J. RANTSCH.
